[57] CLAIM

I claim the ornamental design for a line threader, as shown and described

DESCRIPTION

FIG. 1 is an isometric view of the line threader showing my new design;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a front view thereof in a first alternate position shown on a reduced scale;

FIG. 9 is a rear view of FIG. 8;

FIG. 10 is a front view thereof shown in a second alternate position.
